CLAIM

The ornamental design for detector for use in monitoring empty intravenous infusion containers, as shown and described.

DESCRIPTION

FIG. 1 is a front elevational view of a detector for use in monitoring empty intravenous infusion container showing my new design;

FIG. 2 is a right side elevational view with the left side being a mirror image thereof;

FIG. 3 is a top plan view thereof;

FIG. 4 is a bottom plan view thereof;

FIG. 5 is a rear elevational view thereof;

FIG. 6 is a front perspective view thereof; and

FIG. 7 is a rear perspective view thereof.

FIG. 4

FIG. 3

FIG. 1
